Assignor to
Hiram House of Troy, N.Y.
Letters Patent No 492, Dated Aug 31st 1852

The schedule referred to in these Letters Patent and making part of the same

To all whom it may concern:

Be it known that I, Samuel A. House,
of Mechanicville in the County of Saratoga & State of New York, have invented
or produced a new and original design ^{of furnace stove plate.} for a stove which I call the "Volun-
teer" and I do hereby declare that the following is a full, clear and exact de-

scription of the same, reference being had to the annexed drawings making a part of this specification in which fig. 1. is a direct view, and fig. 2. a transverse sectional view of the same showing the curvature of the plate.

The ornamental design of my stove plate consists in the arrangement of arabesque scrolls (a a a a) disposed around the borders of the plate, and in the scroll center pieces (b) & (c) arranged on the panel of the plate.

Having thus described my design of stove plate,

What I claim as new and desire to secure by Letters Patent, is the ornamental design and configuration of stove plate the same as herein described, and represented in the annexed drawings-
